UNITED STATES PATENT OFFICE.

LOUIS WILHELM, OF NEW HAVEN, CONNECTICUT, ASSIGNOR TO GLOBE OPTICAL COMPANY, OF BOSTON, MASSACHUSETTS, A CORPORATION OF MASSACHUSETTS.

LENS-CUTTING MACHINE.

1,186,254.

Specification of Letters Patent.

Patented June 6, 1916.

Application filed June 24, 1915. Serial No. 36,156.

To all whom it may concern:

Be it known that I, LOUIS WILHELM, a citizen of the United States, and resident of New Haven, in the county of New Haven and State of Connecticut, have invented an Improvement in Lens-Cutting Machines, of which the following description, in connection with the accompanying drawings, is a specification, like letters on the drawings 10 representing like parts.

My present invention is an improvement in the machine shown in the patent to W. W. Slade and H. F. Bower, No. 813,459, dated Feb. 27, 1906, and the object of the invention 15 is to improve and perfect a lens cutting machine of that type.

In cutting lens a high grade of work is required, because of the brittleness of the material being worked, *i. e.* glass, and also 20 because an extremely great degree of skill and delicacy of operation is requisite. In the machine of said patent, difficulty has been experienced in some lines of work, particularly on extra thin material and with 25 unskilled labor, because the operator was obliged to apply the pressure to hold the lens on the cutting bed, manually. This action necessarily resulted in a variable and 30 uneven holding pressure on the glass being cut, oftentimes a considerable pressure being applied by the operator, through one hand operating the lever and holding the glass against the cutting point, and the other pressing downwardly while rotating the 35 gears and operating the machine. The operator's attention being necessarily fixed on the cutting, he would unconsciously press more or less on the hold-down, and consequently the glass was apt to slip in some 40 instances or actually be broken in others, since the operator never knew exactly the degree of force being applied to the lens. My present invention aims to eliminate these 45 difficulties and to provide an automatic hold-down for a lens cutting machine, which will, at all times, secure the lens on its bed while permitting the latter to rotate during the cutting operation, entirely freeing the operator from any manual action to hold the glass in 50 position, while yet enabling the operator to press the lens against the cutter as strongly or as lightly as is desired. I accomplish this result by having a hold-down operated by spring tension, entirely independently of 55 the raising and lowering of the cutting bed

during cutting operation, which raising and lowering is done by a hand lever.

Other details of construction, novel combination of parts, and important advantages will be hereinafter pointed out and claimed. 60

Referring to the drawings illustrating a preferred embodiment of my invention, Figure 1 is a front view of the lens cutting machine illustrated in said Slade and Bower patent, wherein my invention is embodied in 65 preferred form; Fig. 2 is a cross sectional view on the lines 2—2 of Fig. 1; Fig. 3 is a cross sectional view on the lines 3—3 of Fig. 2; Fig. 4 is a side view of my novel form of hold-down detached from the lens 70 cutting machine; and Fig. 5 is a view of the hold-down, looking from the bottom upwardly as same is shown in Fig. 4.

I prefer to embody my invention in the lens cutting machine of the Slade & Bower 75 patent already mentioned, and therefore I have not herein illustrated each and every detail of construction of the cutter shown in said patent, reference thereto being hereby made for a further full and more complete 80 illustration of the details of pattern, follower construction, etc.

The lens cutting machine comprises the hollow base 1, preferably of metal, having an upstanding standard 2, which standard 85 carries lugs 3 and 4 at one side, between which lugs is pivotally secured a carrier arm 5 which projects forwardly and is formed to carry both the diamond cutter and the follower which co-operates with the pattern in determining the course of movement of said cutter as the lens is revolved under it. This carrier has at its forward end forked arms 6 and 7, in which is pivotally secured a holder 8 having an offset portion 9 resting 90 on the lower forked arm 7. Slidably held in the offset portion 9 is a block 10 adapted to be moved to and fro by a thumb nut 11 and with its forward face concaved to rest against the pattern at two points, for better 95 operation during rotation of the pattern against said block. An indicator 12 is so secured to the block 10 that it will point on a scale 13 as the block is manipulated inwardly or outwardly by the thumb nut 11. 100 The standard 2 also carries forwardly projecting arms 14 and 15 which are adapted to receive bearings for a vertical shaft 16 which is positioned centrally of the base 1, and to which is removably secured the pattern 17. 110

in height and position to coöperate with the sliding block 10 on the holder 8. The block 10 is held in yielding engagement with the pattern 17 by means of a spring 18 which 5 has one end secured to the carrier 5, and the other end attached to a chain 19, which chain is adapted to fit over a rod 20 secured to the standard 2, and thus provide an adjustment for tension through interchange of 10 any of the links in the chain. On the shaft 16 is secured a gear 21, having a handle 22 so that said gear may be rotated, which gear meshes with a pinion 23 mounted on a vertical shaft 24 extending downwardly in the 15 standard 2 and carrying near its base a corresponding pinion 25 arranged to mesh with a gear 26. This gear carries on its upper surface the bed 27, preferably of rubber and in circular form, on which the lens may be 20 positioned, and said gear is mounted on a stem 28 slidably fitting within the central aperture 29 of the boss 30 in said base 1. This stem is adapted to be lifted by the inner end of a lever 31, pivoted at 32 on the 25 ears 33 at the outside of the base 1, which lever is adapted to be oscillated by handle 34 manipulated by the operator. Depression of the lever 34 by the operator acts to raise the gear 26 and lens bed 27 upwardly 30 during rotation thereof, the teeth on the pinion 25 being of sufficient length to permit a considerable range of vertical movement without permitting the teeth of gear 26 to get out of mesh therewith. This vertical 35 movement acts to raise the lens 35 resting on the bed 27 against the diamond cutter 36 and the holder 8. In this position rotation of the handle 22 and of the pattern 17 and gear 26 in timed relation against the cutter 40 while said cutter is moved to follow the contour of the pattern 17, through the tension of the spring 18, accomplishes the cutting action, as above briefly explained and as 45 more fully explained in the Slade and Bower patent.

In order to effectually hold the lens 35 on the elastic bed 27 without interfering with the vertical movement of the gear 26 nor with its rotation, nor with the action of the 50 cutter thereupon, I provide a novel form of hold-down. The base 1 has its central portion adjacent the boss 30 in which the stem 28 is mounted, raised slightly as indicated at 37, Fig. 3, to provide a bearing and retainer 55 shoulder for the horizontal plate 38 of the hold-down, which plate is apertured at 39 to fit loosely about the stem 28 of the gear 26, and is recessed at 40 to fit upon the raised portion 37. This plate 38 is thus adapted to 60 swing loosely around the stem 28 of the gear 26 and to be raised and lowered with it. The plate 38 is extended outwardly beyond the base and is formed into a socket member 41 having a recess to receive a spring 42 and 65 a forked portion adapted to bear against a

lever 43 which is pivotally mounted at 44 in a pair of forks 45. This lever extends inwardly and centrally of the base 1 carrying the hold-down 46 which is connected therewith by a universal ball and socket joint at 47, see Figs. 3 and 4.

The action of the spring 42 tends to force the lever with its outer end carrying the hold-down 46 downwardly against and upon the lens 35 firmly upon the elastic bed 27. 75 This arrangement effectually holds the lens in position with a constant and unvarying degree of pressure, irrespective of the pressure supplied to the lever handle 34, and requires no downward holding pressure 80 whatever on the gear handle 22. Formerly the operator was obliged to exert a lens-holding pressure upon the handles 34 and 22, in addition to that required to rotate the gear, operate the machine, and hold the lens 85 pressed upwardly against the cutter 36. I prefer to extend the lever 22 backwardly and to flatten the same sufficiently to form a convenient thumb holding surface 48, and to provide a correspondingly rigid finger holding surface 49, the latter formed on the exterior of the socket 41 to facilitate raising the hold-down 46 against the compression of the spring 42. A latch 50 may be conveniently pivoted to the lever 43 at 51, which latch may be provided with a notch 52 to catch on a pin 53 positioned in a slot 54 in the finger hold 49, through which slot the lower end of the latch 50 may be guided, as clearly shown in Fig. 3. When it is desired 95 to release the lens 35, the lever 43 is oscillated on its pivot and the latch 50 snapped into position so that the notch 52 will catch on the pin 53 and retain the hold-down 46 removed from the lens to permit the latter 100 being removed or positioned. Slides or bosses 55 are formed on the lower part of the plate 38 to rest on the top of the base 1, and act as a bearing for the hold-down. The 105 usual centering pin 56 in the center of the gear 26 is also provided as explained in the 110 Slade and Bower patent.

The operation of my improved lens cutting machine and the importance and advantage of the lens holding means being independent of the lever pressure exerted by the operator on the handle 34 or on the gear rotating handle 22 will be readily appreciated. The operator is enabled to concentrate his attention on the cutting action, the lens is held more uniformly than when hand pressure is involved, and I find that it is even feasible to permit unskilled operators to do this work, owing to the above mentioned advantages. Furthermore the cutting is more uniform, the edges of the lens cut being smoother, unbroken, and hence requiring less grinding when using my machine than was formerly the case. The ball and socket joint at 47 between the lever and 130

hold-down permits both lens and hold-down to rotate freely, while the clamping pressure is retained. If desired, a rubber ring 57 may be carried by the hold-down 46, and a disk 5 or plunger 58 is preferably interposed between the spring 42 and lever 43 to facilitate the operation of the clamp.

Having described my invention, what I claim as new and desire to secure by Letters Patent is:

1. In a lens cutting machine of the kind described, a lens bed support, a yielding hold-down for the lens, comprising a horizontal plate carried by the lens bed support, a pivoted lever mounted on said plate, carrying at one end a hold-down by a universal joint connection, and yielding means to actuate said lever and hold-down into lens clamping position.

2. In a lens cutting machine of the kind described, a lens bed support, a yielding hold-down for the lens, comprising a horizontal plate carried by the lens bed support, a pivoted lever mounted on said plate, carrying at one end a hold-down by a universal joint connection, a spring to actuate said lever and hold-down into lens clamping position, a housing for said spring, and a latch to hold the lever in raised position against the compression of said spring.

In testimony whereof, I have signed my name to this specification, in the presence of two subscribing witnesses.

LOUIS WILHELM.
